UNITED STATES PATENT OFFICE

RAYMOND LOEWY, OF NEW YORK, N. Y., ASSIGNOR TO WESTINGHOUSE ELECTRIC & MANUFACTURING COMPANY, A CORPORATION OF PENNSYLVANIA

DESIGN FOR A RADIOCABINET

Application filed March 7, 1931. Serial No. 38,986. Term of patent 14 years.

To all whom it may concern:

Be it known that I, RAYMOND LOEWY, a citizen of France, residing at New York, in the county of New York and State of New York, have invented a new, original, and ornamental Design for Radiocabinet, of which the following is a specification, reference being had to the accompanying drawings, forming a part thereof, and in which the figures comprise the front and side views of a radio cabinet bearing and incorporating my design.

The cabinet designated in Figs. 1 and 2 of the drawings by reference numeral 1 is of substantially rectangular form having a height which is considerably greater than

either its width or depth, a narrow shoulder at 3 producing the effect of a slight taper in the cabinet in a vertical direction. A raised panel 5 is provided, extending up the front of the cabinet.

The essence of my invention resides in the general form and relative proportions of the cabinet.

I claim:

The ornamental design for a radiocabinet as shown and described.

In testimony whereof, I have hereunto subscribed my name this 20th day of February, 1931.

RAYMOND LOEWY.
